UNITED STATES PATENT OFFICE.

ROBERT C. JONES, OF NEW CUMBERLAND, WEST VIRGINIA.

AUTOMATICALLY-OPERATED TEMPER-SCREW.

No. 836,384.

Specification of Letters Patent.

Patented Nov. 20, 1906.

Application filed May 5, 1906. Serial No. 315,296.

To all whom it may concern:

Be it known that I, ROBERT C. JONES, a citizen of the United States of America, and a resident of New Cumberland, county of 5 Hancock, and State of West Virginia, have invented certain new and useful Improvements in Automatically-Operated Temper-Screws, of which the following is a specification.

10 My invention relates to new and useful improvements in well-drilling apparatus, and more particularly to an automatic device for letting out or paying out the temper-screw; and it consists in the particular construction, 15 arrangement, and combination of parts which will hereinafter be fully described.

The object of the invention is to provide a device whereby the temper-screw of well-drilling apparatus is automatically let out as 20 the drilling-tools sink deeper in the well.

A further object of the invention is to provide a simple, strong, and durable mechanical device for oil, gas, or Artesian well drilling, which will automatically pay out the 25 temper-screw much more accurately than can be done by the most experienced well-driller.

In describing the invention in detail reference is herein had to the accompanying drawings, forming a part of this specification, in 30 which—

Figure 1 is a side elevation of the invention. Fig. 2 is an inner face view of the ratchet mechanism, and Fig. 3 is an enlarged 35 vertical section through the lower portion of the temper-screw.

Referring to said drawings, in which like reference-numerals designate like parts throughout the several views, 1 indicates the 40 ordinary walking-beam, which has mounted upon its end a spring-supported beam 2, on the front end of which is supported the cross-shaped head 3 of the temper-screw stem 4. Said beam 2 is mounted upon suitable springs 45 5, borne by the end of the walking-beam, as shown, thus forming a yieldable support for said stem.

The temper-screw 6 is supported between the reins 7 of the stem 4 in the usual way and 50 has a longitudinal groove 8 therein in which a key 9, carried by a sleeve 10, in which said screw is longitudinally movable, is adapted to slide. Said sleeve is integral with or is rigidly attached to a bevel-gear 11, which is 55 supported by a supporting-bracket 12, said supporting-bracket being bolted to the rear

face of the jacket 13, which incloses the ordinary boxing 14, carried by the ends of the reins 7, the said rear face of the jacket being made rectangular in form for the purpose instead of rounded, as ordinarily employed. 60

Formed integral with the jacket 13, on the front face thereof, is a boss 15, through which the adjusting-screw 16 ordinarily employed for adjusting the boxing 14 is projected. 65 Journaled upon the boss 15 is a bevel-gear 17, which intermeshes with the bevel-gear 11, and formed integral with the bevel-gear 17 or rigidly attached thereto on its outer face is a pinion 18, which meshes with a gear-wheel 19, 70 journaled upon the outer end of a boss 20, carried by one of the reins 7. Also journaled upon the boss 20 and rigidly attached to the inner face of the gear-wheel 19 is a ratchet-wheel 21, the teeth of which are adapted to 75 be successively engaged by a spring-controlled pawl 22, which is pivotally mounted at 23 upon a lever 24, the inner end of which is loosely mounted on said boss 20 on the inner side of the ratchet-wheel 21. A rod 25, rendered adjustable in length by the employment of a turnbuckle 26, is suspended from the walking-beam 1 at a suitable point, the lower end of said rod being rigidly attached to a slide 27, which is adjustably mounted 80 upon the outer end of said lever 24, a set-screw 28 being provided for securing said slide in adjusted position on the lever.

The drilling-tools being suspended from the temper-screw and the temper-screw being suspended from the spring-supported beam 2, the weight of said tools and cable is borne by the springs 5. These springs are made sufficiently strong to hold the weight of the tools and cable when stationary without being perceptibly compressed; but in drilling when the tools are projected or thrust downward the tools reach forward beyond the length of the beam's movement or stroke to strike bottom, and the momentum 95 of said tools compresses said springs. When the tools reach the limit of their thrust, they immediately rebound, and, through the elasticity of the cable, which elasticity varies according to the depth of the well, the tools 100 rise to a considerably greater height than the distance traversed by the end of the walking beam in making its upward stroke. When the tools rebound, the cable is of course relaxed, removing the weight from the springs 105 as the walking-beam is moving upward, allowing said springs to recoil. When the

2

springs recoil, the reins 7 and temper-screw are raised, or, in other words, the beam 2 rebounds, carrying therewith the temper-screw and its stem. In rebounding, all the parts composing my improvement, with the exception of the rod 25, which is held in fixed relation to the walking-beam, are upraised. The outer end of the lever 24 is held stationary by the rod 25. Hence when the said working parts of the device are upraised, as hereinbefore described, the ratchet-wheel 21 is turned forward with relation to said lever and the pawl 22, withdrawing a tooth of the ratchet-wheel from engagement with said pawl and allowing the next tooth to travel forward into engagement with said pawl. This action results in turning the gear-wheel 19 slightly forward, and through the pinion 18 and the bevel-gears 17 and 11, the sleeve 10 is turned, carrying therewith the temper-screw, paying the latter out slightly.

From the foregoing it will be seen that in drilling a well the springs 5 are placed under tension as the tools are projected downward in the well and that they recoil with the rebound of the tools; and, as is obvious, the temper-screw is let out just so fast as required by the progress made by the tools. When drilling is slow, the length of the thrust of the tools becomes less, resulting in the springs 5 being placed under less tension and paying out the temper-screw slowly, and vice versa.

Mounted on the upper end of the temper-screw 6 and held in place by a nut 29 is a buffer-block 30, having a forwardly-projected beveled end 31, adapted for engagement with a shoulder 32, carried by a pivoted dog 33, when the temper-screw has been let out to a sufficient length to require resetting. When the end 31 of said buffer-block strikes said shoulder 32, the dog 33 is thereby thrust forward with its point 34 against the side of the pawl 22. Then with the next forward turning movement of the ratchet-wheel the pawl becomes disengaged from the said wheel and the point 34 drops into place between said pawl and the lever, preventing it from engaging the teeth of the ratchet, and consequently automatically stopping the further paying out of the temper-screw. As is obvious, the slide may be adjusted on the lever to regulate the length of the stroke necessary to operate the ratchet. This is a desirable feature, owing to the fact that the greater the depth of the well, and consequently the greater the length of the cable employed, the greater becomes the elasticity of said cable and the greater becomes the weight borne by the springs, thus rendering some means of regulation necessary to prevent the temper-screw from being let out too rapidly. It will be noted that the temper-screw is paid out or let out on the rebound of the beam 2 or when the cable is relaxed with the rebounding

tools. A stop 35 is provided on the end of the walking-beam at a suitable point for limiting the downward movement of said spring-supported beam, preventing injury to the springs 5, due to the tools sticking in the well.

Various alterations and changes may be made in the minor details of construction and in the arrangement of parts without departing from the general spirit or scope of the invention. Hence I do not desire to limit myself to the precise construction and arrangement of parts herein shown and described.

Having thus described my invention, what I claim as new, and desire to secure by Letters Patent, is—

1. In a device of the character described, the combination with a walking-beam, of a spring-supported beam mounted on the end of said walking-beam, a temper-screw suspended from said spring-supported beam, and means in operative engagement with said temper-screw whereby the recoil of said spring-supported beam when the drilling-tools rebound actuates said temper-screw to turn, paying itself out.

2. In a device of the character described, the combination with a walking-beam, of a yieldable support mounted upon the end of said walking-beam, a temper-screw having a longitudinal groove therein suspended from said support, and means in engagement with the groove in the temper-screw whereby the latter is actuated to rotate slightly, paying itself out, upon the recoil of said support when the tools rebound.

3. In an automatically-operated temper-screw for oil, gas, or Artesian well-drilling, the combination with a walking-beam, of a spring-supported beam mounted over the end of said walking-beam, a temper-screw suspended from said spring-supported beam, a rod suspended from said walking-beam, and means intermediate said rod and said temper-screw whereby the upward recoil of the spring-supported beam when the tools rebound causes the temper-screw to rotate slightly forward, paying itself out.

4. In an automatically-operated temper-screw, the combination with a walking-beam, of a temper-screw, a flexible connection between said temper-screw and said walking-beam, a rod suspended from said walking-beam, said rod being carried in fixed relation to said walking-beam, and means intermediate said temper-screw and rod whereby the recoil of said flexible connection when the drilling-tools rebound automatically rotates said temper-screw.

5. In an automatically-operated temper-screw, the combination with a walking-beam, of a temper-screw, a flexible connection between said temper-screw and said walking-beam, and means in operative engagement with said temper-screw whereby the recoil

of said flexible connection, permitted by the elasticity of the cable when the drilling-tools rebound after a downward stroke, automatically actuates said temper-screw to rotate 5 forward.

6. In an automatically-operated temper-screw, the combination with a walking-beam, of a yieldable support carried by the end of the walking-beam, a temper-screw suspended 10 from said yieldable support, said temper-screw having a longitudinal slot therein, a sleeve carrying a key in engagement with said slot, means by which said sleeve is rotated upon the recoil of said yieldable support when the drilling-tools rebound, paying out said temper-screw.

7. In an automatically-operated temper-screw, the combination with a walking-beam, of a yieldable support carried by said walking-beam, a temper-screw suspended from 20 said yieldable support, said temper-screw having a longitudinal groove therein, a sleeve through which said temper-screw is slidable longitudinally, said sleeve being in interlocked engagement with said temper-screw, means whereby said sleeve and temper-screw are actuated to rotate upon the recoil of said support when the drilling-tools rebound after 25 a downward stroke, and means for regulating the rotation of said temper-screw, substantially as described.

8. In a device of the character described, the combination with a walking-beam, of suitably-mounted springs carried by said 30 walking-beam, a beam supported by said springs, a temper-screw suspended from the last-mentioned beam, means in operative engagement with said temper-screw whereby the recoil of said springs when the drilling-tools 35 rebound after a downward stroke actuates said temper-screw to rotate, and means for regulating or adjusting the amount of rotation of the temper-screw produced by a stroke.

9. In an automatically-operated temper-screw, the combination with a walking-beam, 45 of a yieldable support carried by the end of said walking-beam, a temper-screw stem suspended from said yieldable support, reins carried by said stem, a temper-screw carried between said reins, said temper-screw having 50 a longitudinal groove therein, a boxing for said temper-screw, a jacket inclosing said boxing, a boss carried by said jacket, a bevel-gear and a pinion journaled in fixed relation to each other on said boss, a sleeve about said 55 temper-screw below said jacket, a key carried by said sleeve in engagement with said groove, a bevel-gear rigidly attached to said sleeve and meshing with the first-mentioned bevel-gear, a bracket carried by said jacket for 60 supporting said bevel-gear and sleeve, a boss carried by one of the reins of the temper-screw stem, a gear-wheel and a ratchet-wheel journaled in fixed relation to each other on the last-mentioned boss, said gear-wheel 65 meshing with said pinion, a lever having one end journaled upon the last-mentioned boss adjacent to the ratchet-wheel, a pivoted spring-controlled pawl carried by said lever for engaging said ratchet-wheel, and a rod 70 suspended from the walking-beam and having its end adjustably connected to said lever whereby the lever and pawl are held stationary when the yieldable support carrying the temper-screw and its correlated parts, including the ratchet-wheel, recoils with the rebound of the drilling-tools, slightly rotating said ratchet-wheel, and, through the intermediate mechanism, slightly rotating said 75 temper-screw.

In testimony whereof I affix my signature in presence of two subscribing witnesses.
